LOOSE LEAF BINDER

Filed May 25, 1922

Fig. 5

Inventor,
Joseph Kahn,

By official sole trustee & Secy. Atty.

UNITED STATES PATENT OFFICE.

JOSEPH KAHN, OF CHICAGO, ILLINOIS.

LOOSE-LEAF BINDER.

Application filed May 25, 1922. Serial No. 563,512.

To all whom it may concern:

Be it known that I, JOSEPH KAHN, a citizen of the United States, and a resident of Chicago, in the county of Cook and State 5 of Illinois, have invented certain new and useful Improvements in Loose-Leaf Binders, of which the following is a specification.

This invention relates to improvements in loose-leaf binders, and more particularly to 10 binders characterized by the use of hook-like fastening members mounted on one of the binder covers and engaging the adjacent ends of binding posts fixed to the other binder covers.

15 The object of the invention is to provide a new and useful binder, including in its construction a simple, substantial, and positive locking mechanism, hereinabove referred to as hook-like fastening members, 20 together with means for actuating the locking members, simultaneously.

Further and other advantages will be brought out in connection with the description which follows, and in connection with 25 the accompanying drawings, wherein—

Fig. 1 is a perspective view of a binder in open position and showing the locking mechanism with portions broken away to reveal the enclosed parts.

30 Fig. 2 is a view in cross-section through the binder in closed position, and the locking mechanism, as taken on line 2—2 of Fig. 1,

Fig. 3 is a detail view of the locking parts 35 in locked position, as taken on line 3—3 of Fig. 1,

Fig. 4 is a perspective view of a key used in conjunction with the operating mechanism shown in Fig. 1,

40 Fig. 5 is a view in perspective, showing a modified form of opening mechanism, and

Fig. 6 is a view in perspective of another modified form of operating mechanism.

A loose-leaf binder, in the typical form, 45 consists of cover members 1 and 2 joined together by a back portion or section 3 to which the cover members are hinged in the manner long practiced in the art of book-making. Between the cover members are held the binder sheets or leaves 4, to any thickness not to exceed the width between covers, said leaves being held in place by means of transverse binding posts 5, 5, extending between

covers and located near the back section 3. Holes punched in the marginal portion of 55 the leaves are engaged by the posts.

In the binder, herein illustrated, the cover members are stiff, being made of one or more plies of card board covered with leather or other binding material. The book section 3 60 is also stiff, although it may be relatively flexible or limp, if so desired. As shown in Fig. 2, the posts 5, 5 are cylindric rods fixed or anchored in a stiff rail 6, extending transversely of the bottom cover 2, parallel with 65 and adjacent to the flexible hinge forming connection between the cover 2 and back section 3. The rail 6 is preferably embedded or inlaid in the body of the cover. In the free ends of the posts are formed eyes 5^a 70 extending diametrically therethrough in alignment with each other.

Along the inner edge of the top cover 1 and adjacent to the connecting hinge is a shallow metallic casing 7 which encloses 75 and supports the locking members and operating parts, the former being movable into and out of engagement with the eyes 5^a of the parts 5.

The casing 7 is preferably constructed in 80 two parts, namely, a flat bearing plate 8, and a flanged cover plate 9 secured to said bearing plate by suitable fastening means. The marginal flanges 9^a of the cover plate abut against the bearing plate, spacing them 85 apart and forming a shallow chamber therebetween. Along the inner edge of the bearing plate is a tubular flange 10, which projects bodily beyond the hinged edge of the cover 1 and, when the binder is closed, occupies a position immediately over the ends of the posts 5, 5. The ends of the tubular flange terminate short of the ends of the bearing plate and likewise short of the cover edges. Intermediate the ends of the tubular 90 flange are cut notches or recesses 10^a, 10^a adapted to register with the free ends of the posts 5, 5, and permit locking action between the eyes 5^a, 5^a and the locking hooks, hereinafter to be described. Along 100 the opposite side of the casing the bearing plate 8 is extended beyond the cover plate, forming a flange 11 which extends between the layers of card board forming the cover 1, the outermost layer extending the full 105 width of the casing and the innermost layer

terminating in abutting engagement against the edge of the cover plate 9, as clearly shown in Fig. 2. Several rivets 12, 12 are passed through the flange 11 and the outermost layer of card board, thus firmly anchoring the casing 7 in place. In constructing the binder the casing is embedded in the cover so that the inner surfaces of both are flush, the casing being covered over by the layer of finishing material which is applied after the casing has been secured in place.

Pivoted upon the bearing plate 8 are a plurality of similar fastening members or hooks 13 spaced apart throughout the length of said plate at the ends and central portion thereof. Each fastener or hook is pivoted at 14 intermediate its ends, and extends transversely of the plates in flatwise contact therewith, the hooked end portion 13^a extending substantially in line with the tubular flange 10, as clearly shown in Fig. 3. The movement of the fastening members imparted by actuating parts engaging the rounded head 13^b at the inner end of each, carries the outer hooked portion across the notches 10^a into the tubular flange located adjacent each fastening member, the extremity being inserted and withdrawn from the opening in the tubular flange. On the opposite side of the notch the tubular flange is slotted lengthwise as at 10^b, thereby providing a supporting slot in which the U-shaped portion of the hooked end travels.

The relation of the fastening members 13 and the posts 5 is such that the movement of the former acts to engage and disengage the eyes 5^a at the free ends of the latter when the ends of the posts are brought into registering relation with the notches 10^a of the tubular flange 10. In this position the ends of the hooked portions are brought into alignment with the eyes of the posts so that in the endwise movement of the fastening members the ends thereof pass through the eyes and into the open ends of the tubular flange beyond, thus providing hinges or pins upon which the free ends of the posts may turn in the opening and closing of the binder. It is to be observed that the end portions of the hook are thus held within the slots 10^b and are guided into and out of locking position, thereby affording a rigid and secure locking device.

The means for actuating the fastening members comprise a flat endwise movable bar 15 mounted between the plates 8 and 9 and held from lateral displacement by guides 16 struck up from the metal of the bearing plate 8. Along the inner edge of the strip 15 are provided notches 17, which receive the rounded ends 13^b of the fastening members 13 so that the shifting of the bar endwise actuates the fastening members into locking and releasing positions. The endwise movement of the strip is limited by

longitudinal slots 15^a through which pass the rivets 10, connecting the top and bottom plates 8 and 9.

Several means may be adopted for manually operating the strip or sliding bar 15, depending largely on choice or the particular style of binder.

In Fig. 1 a key-operated actuating mechanism is shown which consists of a short lever 18 pivoted to the bearing plate 75 adjacent the inner edge of the bar 15 and engaging a substantially semi-circular cam recess 19 therein. Spaced a short distance from the edge of the bar and on opposite sides of the lever 18 are stop members 20, 20, 80 acting to limit the movement of the lever, and to stop the same in its extreme positions substantially parallel to the bar and in abutting contact with the ends of the recess 19. Thus in the extreme positions the lever 85 serves as a lock, preventing movement of the bar other than by manipulation of the lever. At the pivoted end of the lever is a square head 21 facing upwardly and adapted to receive a key 22 (Fig. 4) having a square 90 socket 22^a. In the cover plate an opening (not shown) is provided to receive the key, access being had thereto from the inside of the top cover 1.

A modification of the key actuated operating lever is shown in Fig. 5, wherein a similar form of lever 23 is used, but in place of a key-engaging head, a projection or lug 24 is provided at the free end of the lever. 95 This lug extends through a semi-circular slot 25 formed in the top plate 9 and substantially flush with the inside cover surface. This lug is adapted to be pushed from side to side by the finger or thumb-nail, and offers a simple and satisfactory method of operation where the degree of security is not required, as would recommend the movable key-operated form.

A still different form of operating device, and perhaps a simpler form, is the provision 110 of an up-turned finger 26 (Fig. 6) at one end of the bar, this being provided by extending the bar at one end through and beyond the casing 7, and bending the end at right angles. A depression 27 may be provided in the cover 1, near the edge, in which the finger may move.

Manifestly, any one of the methods and means may be used for operating the bar, which in turn actuates the locking members simultaneously. Furthermore, the complete locking mechanism may be duplicated at both sides of the binder, thus permitting the removal of the leaves from front or back.

Among the advantages of a binder constructed as herein set forth may be mentioned the simplicity of structure and ease of operation. A further advantage resides in the concealment of the parts, not only within the covers, but the positioning of the

operating devices on the inside of the covers, thereby making it possible to introduce the loose-leaf arrangement in minute-books, diaries, and records having the more elaborate and expensive bindings, without the presence of unsightly parts to detract from the appearance.

The various details of design and structure herein disclosed may be variously modified without departing from the spirit of the invention, and therefore I do not wish to be limited except in so far as the invention is defined in the appended claims:—

1. A loose-leaf binder comprising hinged covers and a back, binding posts anchored in one of the cover members, a lock casing mounted on the other cover member, hooked locking members pivotally mounted in said casing and adapted to be swung into and out of locking engagement with the free ends of said binding posts, and means for actuating said locking members simultaneously.

2. A loose-leaf binder comprising hinged covers and a back, binding posts mounted on one cover, a plate mounted upon the other cover member, hooked locking members pivotally mounted upon said plate and adapted to be swung into and out of locking engagement with the free ends of said posts, and means for guiding the post engaging portions of said locking members into and out of locking engagement with said posts.

3. A loose-leaf binder comprising hinged covers and a back, binding posts mounted on one of said covers and having eyes formed at their free ends, a casing mounted on the other cover and comprising a plate having a tubular marginal flange extending beyond the hinged edge thereof, locking hooks pivoted on said plate and engaging slots formed in said flange, there being formed notches in said flange engaging the ends of said posts in locked position.

4. A loose-leaf binder comprising hinged covers and a back, binding posts mounted on one cover, a casing embedded in the other cover and extending along the hinged edge thereof, locking hooks pivotally mounted in said casing, the hooked ends thereof extending from said casing for engagement with the ends of said binding posts, and means

for guiding said hooks into locking engagement with said binding posts.

5. A loose-leaf binder comprising hinged covers and a back, binding posts secured in one cover, a casing secured to the other cover and provided with a tubular flange extending beyond the hinged edge of said last mentioned cover, locking hooks pivotally mounted in said casing and adapted for engagement with the free ends of said binding posts, said flange being provided with notches to receive the ends of said posts and longitudinal slots adjacent said notches for supporting the post engaging portions of said locking members.

6. A loose-leaf binder comprising hinged covers and a back, binding posts secured to one cover, a plate extending along the hinged edge of the other cover, locking members pivotally mounted on said plate and having hooked extremities adapted to engage eyes in the free ends of said posts, a bar slidable longitudinally of said plate and having operative connection with said locking members, a flange integral with said plate and having notches to receive the ends of said binding posts, and means for guiding the locking members into the eyes of said posts.

7. A loose-leaf binder comprising covers and back hinged together, binding posts mounted on one cover, a casing extending along the hinged edge of the other cover consisting of a base plate having a tubular flange extending beyond the edge of the cover, hooked fastening members pivotally mounted intermediate their ends on said plate and having transverse end portions adapted to engage eyes in the free ends of said binding posts, said tubular flange being provided with notches therein to receive the ends of said posts, and slots extending longitudinally from said notches acting as a guide for the end portions of said fastening members, a bar slidably mounted in said casing and operatively connected with said fastening members, and means for actuating said bar from the exterior of said casing.

In witness whereof, I hereunto subscribe my name this 22nd day of May, A. D., 1922.

JOSEPH KAHN.
